(57) **CLAIM**

The ornamental design for a video camera, as shown and described.

DESCRIPTION

FIG. 1 is a front elevational view of a video camera showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a cross sectional view thereof taken along line 6-6 of FIG. 1;

FIG. 7 is a partially enlarged front elevational view thereof;

FIG. 8 is a partially enlarged front elevational view thereof, wherein the lever is in an alternate position;

FIG. 9 is a partially enlarged front, top, and right side perspective view thereof, shown with the lever in the original position of FIG. 1;

FIG. 10 is a partially enlarged front and right side perspective view thereof;

FIG. 11 is a partially enlarged front, top, and left side perspective view thereof;

FIG. 12 is a partially enlarged front, bottom, and left side perspective view thereof; and,

FIG. 13 is a partially enlarged front, top, and left side perspective view thereof, shown with the lever in the alternate position of FIG. 8.

The broken lines depict portions of the video camera in which the design is embodied that form no part of the claimed design. Additionally, the dash-dot lines denote the boundary of the claim and form no part of the claimed design.
